AERATING SYSTEM FOR ICE CANS

Filed Feb. 15, 1927

2 Sheets-Sheet 2

UNITED STATES PATENT OFFICE.

JOSEPH A. MARTOCELLO, OF PHILADELPHIA, PENNSYLVANIA.

AERATING SYSTEM FOR ICE CANS.

Application filed February 15, 1927. Serial No. 168,266.

My invention relates to can baskets for use in making ice and has particular reference to the air connection of can baskets.

A purpose of my invention is to fasten an air lateral permanently along the outside of a can basket near the top thereof.

A further purpose is to supply a tube construction from a can basket air lateral with a high-pressure orifice between the lateral and a tube adapted to easy removal for cleaning.

A further purpose is to provide removable nozzle connection between an air lateral permanently fastened to the outside of a can basket and a permanent tube inside a can, providing upwardly directed sockets in the lateral and in the tube and either flexibly or rigidly connected nozzles fitting the respective sockets, with a high-pressure orifice in the up-stream end of one of the nozzles.

A further purpose is to provide a feed control valve from a lateral with stuffing box connection to an air tube and with a high-pressure orifice removable for cleaning.

A further purpose is to feed an air lateral fastened to a basket through a nozzle flexibly connected to the lateral and fitting into an air check valve on an air header during freezing and into a pocket on the basket during handling of the basket.

Further purposes will appear in the specification and in the claims.

I have preferred to show one main form only of my invention with a slight modification and have selected a form that is practical and efficient in operation and which illustrates particularly well the principles involved.

Figure 1 is a broken perspective view illustrating one form of my invention adapted to a can basket of the shell cooler type.

Figure 2 is a broken fragmentary section taken upon the line 2—2 of Figure 1 to enlarged scale.

Figure 2^a is a fragmentary view similar to Figure 2 but showing a modification.

Figure 3 is a fragmentary section taken upon the line 3—3 of Figure 2.

Figure 4 is a fragmentary sectional elevation of an air check which may be used on the basket.

Figure 5 is a fragmentary section, corresponding to line 3—3 but showing a second form.

Figure 6 is a sectional elevation of a part of Figure 5, the section being upon line 6—6.

Figure 7 is a fragmentary perspective showing the air lateral inside the basket.

Figure 8 is the fragmentary side elevation of the connection with the lateral seen in Figure 7.

Like numerals indicate like parts in all figures.

Describing in illustration and not in limitation and referring to the drawings:

In modern ice manufacturing the ice cans are frequently handled in basket units, usually at least five or six cans to a basket. After the freezing operation is complete the unit is lifted away from the freezing floor and transferred first to a thawing tank where it is dipped into warm water until the ice is thawed loose from the cans and then to the dump where the basket is inclined or tipped over until the ice slides from the cans. The cans of the unit are then refilled with water and the unit is taken back to the freezing floor for the freezing of another batch of ice.

The types of basket vary considerably but in this application I have illustrated my invention as applied to a basket of the shell cooler type though I am aware that it is well adapted to use with other types of basket.

In the shell type cooler the brine of the freezing tank is continuously circulated through the cooler and around the tank to freeze the water in the ice cans. The cans of a basket unit do not have to be spaced from one another to any extent as there are no coils between adjacent cans.

The ice can basket of Figure 1 comprises a frame structure 15 around the upper ends of the cans 16, the cans being firmly fastened into the frame structure by suitable support around above and below each can band 17 at the top of the can.

The side plates 18 and 19 carry metal strips 20 engaging the bottoms of the bands across the short sides of the cans and transverse tie rods 21 between the side plates engage and support the bottoms of the bands of adjacent cans across the long sides of the cans.

Each end tie rod 22 engages and supports the band of one can only while each of the other rods has to engage and support the adjacent sides of two cans.

The transverse supporting tie rods between the side plates are placed between successive cans except where replaced near one end of the basket by the lifting plates 23 and 24 and near the other end of the basket by lifting

plates 25 and 26. Each of these lifting plates carries a strip 27 engaging and supporting the bottom of the band of its adjacent can.

The lifting plates are shown between the 5 first and second cans from each end and have their ends firmly fastened to the side plates. The plates of each pair carry between them a lifting pin 28 for engagement by a suitable hook for use in transferring the basket from 10 place to place.

The cans are firmly supported at their tops 29 by structure which firmly fastens the cans against movement through the top of the basket during tipping.

15 In the structure shown in Figure 1 an air lateral 30 is fastened along the outside of one of the side plates with an inlet portion 31 bent at right angles to extend part way across the end can, to which it is suitably fastened as by 20 means of a bracket 32 upon the can band.

There is flexible connection 33 between the lateral fastened to the bracket and a permanent air header 34 upon the freezing floor.

The flexible connection 33 is permanently 25 fastened at one end and disconnected at the other before lifting the basket from the freezing floor and when disconnected both the lateral and header should preferably be sealed—the lateral against entry of water or dirt during tipping, thawing and filling and the header against escape of air.

30 In Figure 1 the flexible connection 33 is permanently fastened to the header and the inlet fitting 35 upon the lateral has a taper 35 socket 36 which receives a corresponding taper nozzle 37 on the end of the connection 33, (see Figure 4).

A sealing pocket 38 tapered to fit the nozzle 39 is mounted in a convenient place on the floor 40 to receive and seal the nozzle 37 when disconnected from the fitting 35 and the fitting 35 is provided with a ball check 39 spring-pressed toward its seat 40 to seal the opening into the fitting.

45 When inserted into the socket 36 the end of the taper nozzle 37 pushes back the ball 39 and air enters the lateral through slots 41 in the end of the nozzle. These slots avoid any sealing of the nozzle by the ball.

50 When the freezing operation is over the nozzle 37 is taken out of the check fitting and inserted into the sealing pocket upon the floor structure of the tank, the check fitting automatically closing as the nozzle is taken out.

55 The lateral passing through the side plate 18 makes a right bend and extends horizontally along the outside of the side plate to feed the cans of the basket.

The drop tubes are illustrated in Figure 1 60 as permanently fastened in one corner of each of the cans, the top of each air tube being provided with a taper socket 42.

Removable connection is made from the lateral to each of the air tubes.

65 As illustrated in Figure 2 a ferrule 43 hav-

ing tapered interior 44 is inserted into the top of the lateral, and the nozzles 45 and 46 fit the sockets of the tube and ferrule and are flexibly connected together at 47.

The nozzles extend upwardly and are then 70 bent to present horizontal facing shanks 48 and 49 above the lateral, the nozzle 45 is bent in a horizontal plane to pass through a suitable perforation 50 in the side plate and is then bent downwardly to enter the air tube. 75

The shanks 48 and 49 are corrugated to maintain firm hold upon the flexible connection 47.

Desirably a high-pressure orifice 51 is provided in the approach end of one of the nozzles 80 45 or 46, shown in the figure as in the double elbow nozzle 45.

There is some advantage in having the high-pressure orifice in the double bend elbow 85 nozzle 45 rather than in the elbow nozzle 46 in that the air then enters the nozzle 46 at much lower velocity than would be the case if the small orifice were in the nozzle 46, which results in less tendency for dirt to enter the line of the air tube. 90

In Figure 2^a I have shown the flexible pipe 47 connected with the lateral by the elbow fitting 49' which is threaded into the lateral instead of being a friction fitting in a nipple therein. The connection shown with the 95 flexible tube may be of any suitable form.

In Figures 5 and 6 I have shown a connection between the lateral and the air tube containing a removable section of small diameter which section can be removed not only to 100 make the diameter adjustable by replacement of sections having different diameters but to clean out trapped foreign matter which may clog the section.

Within the lateral is screwed a fitting 52 having a small opening 53 well above the bottom of the tube to keep it out of the line of dirt and scale. The upper end of the fitting is provided with a seat 54 which may taper if desired and which receives the end 55 of a 105 U connection 56. The other end 57 of the U 110 connection fits into the air tube.

About the end 55 of the U connection I 115 form a stuffing box containing packing 58 tightened about the tube by nut 59 screwed upon the exterior thread 60 of the fitting.

Between the lateral and the end 55 of the U I provide a tapered transverse bore 61 for a tapered plug 62 which may be turned by handle 63 so as to act as a cut off valve in position at right angles to that shown in Figure 6 or to allow passage of the air through a restricted opening 64 in the position shown in Figure 6. The plug will ordinarily be retained in position by friction alone and usually will not require any fastening to hold it in position. 120

The opening 64 comprises a pressure orifice which may be picked to suit anticipated conditions and which may be changed without 125 130

changing the fitting where these conditions change or are found not to be as anticipated.

The **U** passes through any suitable opening such as that shown at 50 but need not be extended laterally as at 48 since the fitting with which it is to connect can be located directly outside of the opening 50. This opening, of course, for either form must give enough room for the seating of the member 45 within the tube in the one case and for seating the **U** within the tube and fitting in the other.

In Figures 7 and 8 the air lateral is placed within the basket and connection with the tubes in the cans is made through a valve fitting of the same character as that seen in Figure 6, but connecting into the bottom of the lateral and extending downwardly, as distinguished from the connection with the top of the lateral and extension upwardly seen in Figure 6. The terminal 65 from the fitting is intended to fit directly into the top of one of the tubes 66 within the can.

The lateral will be permanently attached to the inside of the basket, ordinarily to the side frame, when it is desired to leave the lateral in connection with the tubes, relying upon the taper of the cans to ensure that the ice will clear the lateral when the ice is being emptied from the cans, but will be removed along with the terminals 65 where the designer desires to clear the interior of the basket at the top from all fittings which might break this ice or impede it in its movement from the cans.

In view of my invention and disclosure variations and modifications to meet individual whim or particular need will doubtless become evident to others skilled in the art, to obtain all or part of the benefits of my invention without copying the structure shown, and I, therefore, claim all such in so far as they fall within the reasonable spirit and scope of my invention.

Having thus described my invention, what I claim as new and desire to secure by Letters Patent is:—

1. In an ice can basket, a frame work, a plurality of cans supported thereby, a lateral upon the outside of the basket, rigidly attached thereto, means for connecting the lateral with a header, an air tube for each can rigidly fastened against a wall of the can and air connection for each can from the tube to the lateral passing through an aperture in the frame work.

2. In an ice can basket, a pair of sides, one of them apertured, connection between the sides forming a frame, cans supported in the frame, a lateral rigidly secured at the outside of the side having the apertures, an air pipe for each can, adjacent an aperture and secured in the corner of the can, a nozzle and pipe for each air pipe extending upwardly

from the pipe, outwardly through the corresponding aperture and then in the general direction of the length of the lateral, a flexible tube thereon and a nozzle connected with said tube and fitting into the lateral.

3. In an air can basket having side frame walls, one of which is apertured opposite the can, a plurality of cans between the side frame walls, a lateral along the outside of the apertured side wall, a plurality of air pipes one against a wall of each can terminating in a tapered opening and a plurality of connections between the respective pipes and the laterals, each comprising a tapered nozzle fitting the pipe, extending downwardly through the corresponding opening and then parallel with the lateral, a fitting for each connection engaging with the lateral and a flexible tube connected between the fitting and the nozzle.

4. In an ice can basket having side frame walls, one of which is apertured opposite each can, a plurality of cans in the basket, a lateral along the apertured side wall having outlet openings spaced, longitudinally of the lateral, from the apertures, a plurality of air pipes, one in the corner of each can and terminating in a tapered opening and a plurality of connections between the respective pipes and the laterals comprising each a tapered nozzle fitting in the pipe, extending upwardly and outwardly through the corresponding opening, then parallel with the lateral, a flexible tube connected with the nozzle and a connection between the other end of the flexible tube and the lateral outlet.

5. In an ice can aerating system, side frame walls, an ice can, a lateral, a tube in the can, and a connection between the tube and lateral extending upwardly from each and passing through one of the walls.

6. In a can basket, a frame work for the basket, a plurality of cans therefor, a plurality of air tubes, one for each can, having upwardly directed sockets, a lateral extending past the cans and having an upwardly directed socket for each can and an air connection between each socket of the lateral and the corresponding air tube, passing through the frame, flexible at an intermediate point, and having a nozzle at one end.

7. In a can basket structure, a framework for the basket apertured at one side, a plurality of cans therein, a plurality of air tubes fixed in the cans close to the apertures at the one side of the frame, a lateral along the outside of the frame and flexible connections engageable at one end with the lateral to secure air supply, and terminating at the passage end in laterally and downwardly directed nozzles for engagement with the respective tubes.

JOSEPH A. MARTOCELLO.
